UNITED STATES PATENT OFFICE.

LOUIS K. JOHNSON AND A. AUGUSTUS LOW, OF BROOKLYN, ASSIGNEES
TO THE ALDEN TYPE MACHINE COMPANY, OF NEW YORK, N. Y.

TYPE-DISTRIBUTING APPARATUS.

SPECIFICATION forming part of Letters Patent No. 392,806, dated November 13, 1888.

Application filed July 11, 1885. Renewed June 2, 1888. Serial No. 275,898. (No model.)

To all whom it may concern:

Be it known that we, LOUIS K. JOHNSON and A. AUGUSTUS Low, citizens of the United States, residing in the city of Brooklyn, county 5 of Kings, and State of New York, have invented certain new and useful Improvements in Type-Distributing Apparatus, of which the following is a specification.

Our improvements relate to the class of type-distributing apparatus heretofore described and claimed by us, in which the types are dropped by hand into receiving-conduits, from which they are transferred to the type-containing channels for use in the "setter" by a 15 reciprocating comb pusher or forwarder.

One of the leading features of our present invention consists in the means employed for preventing "backlash"—*i. e.*, all vibratory or retractile movement of the types in the type-containing channels. We have elsewhere set forth the cause and effect of this backlash movement and described positive means for preventing the same; but such means are purely mechanical and afford an amount of 20 resistance to the forwarding of the types which we desire to avoid, as well as the consequent wear upon the types themselves. We therefore in the present case construct the type-channels at or near their extremities which 25 adjoin the type conduits and forwarder with one or more internal bends or protuberances in their side walls, whereby the types in the column are made to deviate slightly from perfect alignment in the channel in such manner 30 as to cause a slight resistance to the passage of the types in either direction, creating sufficient friction to counteract all tendency to backlash or spring in the line of types already forwarded, while affording comparatively 35 slight resistance to the action of the pusher.

We are aware that in Patent No. 18,175, issued to Alden, September 15, 1857, a type-channel is shown in which a lateral deviation in the body of the channel itself is formed, and 40 we do not herein seek to claim such construction, the novelty in our construction being the contraction of the type-passage at one or more points for the purpose of effecting a deviation in the path of the types from the 45 straight or central line of the channel. To still further contribute to this result, but

more especially for the purpose of counteracting the tendency of the line of types to slide longitudinally in the channel while the latter is being handled or transferred, we form one 55 or both of the side walls of the channels with transverse corrugations or otherwise slightly roughen their inner surfaces, so as to afford a frictional contact with the edges of the contained types which will tend constantly to oppose any change in position. By these simple means we obviate any tendency in the forwarded types, to interfere with or obstruct those which follow and increase the stability of the line as a whole. By dispensing with 60 the use of spring or other mechanical latches for this purpose we reduce the wear upon the type, while retaining the advantages of automatic action.

In this connection our invention also includes a comb pusher or forwarder, the individual teeth of which are formed of different lengths or degrees of projection, corresponding relatively to the particular thicknesses of the individual types which each is designed to 70 forward. By this means each type may be forwarded an appropriate distance from the end of its conduit proportionate to its own thickness, and the relations of the last preceding type to the next succeeding type will 75 be the same relatively for all the characters. Heretofore the pusher has forwarded all types alike and to a common line irrespective of their diversity in thicknesses, so that in order to obtain sufficient space for the descent of the 80 thicker characters into the type-channel the thinner characters have necessarily been forwarded to such an extent as to leave an undue degree of space or "play" for the descent of succeeding types, thus admitting of 85 such thinner types turning axially within the channel before the pusher forwards them.

As heretofore constructed by us in our duplex receiving-bank the conduit-plates have been placed back to back at opposed angles, 90 their upper extremities converging toward each other, and have been permanently attached to the frame, although their lower ends have in some cases been adjustable. In our present construction we arrange the conduit- 95 plates, which are "struck up" in sheet metal, so that they are vertical in position and sup-

port their opposite extremities between vertical shoulders in such manner that the plates may be readily inserted or withdrawn.

As the extremities of the conduit-floors enter 5 into containing-channels, and thereby constitute a means of centralizing and holding the latter in position laterally upon the table, we design, in cases where the apparatus is to accommodate several sizes of type-channels, &c., 10 to make the conduit-plates in two sections, the upper one of the full width of largest type to be used and the lower plate to consist of one of a series of plates formed with conduits, the upper side walls of which coincide with 15 and form continuations of the side walls of the upper plate, from which point said side walls converge to the size of the types and channels to be used. Thus by simply removing the upper and lower plates and substituting the 20 appropriate plate for the lower and replacing the upper thereon the apparatus is adapted to a different size of type, it being understood that the channels in the receiving-plates are of the maximum width.

25 We are aware that in our application, Serial No. 156,604, intermediate sections with converging walls are used upon the table of the machine for connecting the type-conduits with type-containing channels having type-passages of 30 less width than those in the said conduit-plates; also that in A. Augustus Low's application, Serial No. 159,693, a combined reciprocating type receiver and forwarder is provided with a removable nozzle or lower section adapted to 35 engage with and conduct types in like manner into a type-containing channel formed with a type-passage of less width than that of the type-conduits in the receiver, and we therefore simply seek to cover herein the special 40 construction and combination of parts shown and described. The space between these vertical conduit-plates which is rendered necessary by the width and extent of motion of the double-comb pusher underneath is utilized by us by forming or supporting therein 45 a series of open space or odd sorts boxes or compartments, their position between the two divisions of the bank rendering them especially convenient and useful in distribution, 50 especially for the reception of the numerous spaces always present in composition.

Our invention also includes the special means employed for binding the receiving-plates together, consisting of adjustable bearings attached to the supporting-posts and ratchet-braces which support and lock the latter against backward movement.

Finally, our invention consists in forming the channel-supporting beds each in two sections, which are adjustable with relation to each other, for the purpose of adjusting the apparatus to differences in the lengths of the different series of channels used.

In the accompanying drawings only sufficient 65 detail of the apparatus is shown to illustrate the special features of construction claimed

in the present case, the general features of which are the same in construction and operation as those shown and described in our recent applications. Accommodation is shown 70 for only a comparatively few channels, and the latter are shown of less length than in actual use.

Figure 1 is a plan upon a reduced scale illustrating the construction of our improved apparatus; Fig. 2, a longitudinal section of the same; Fig. 3, an elevation of the central portion of the same partially broken away to show one of the segmental gears for effecting the movement of the receiver-plate carriage. 80 Fig. 4 is a horizontal section, full size, through opposite extremities of one of the conduit-plates and adjoining parts of the frame. Fig. 5 is a front elevation, full size, of the opposite extremities of one of the conduit-plates provided with a movable lower section having converging side walls; Fig. 6, a vertical section, full size, through one of the conduit-channels and the inner extremity of one of the type-containing channels, illustrating the use 85 of the concave extension of the conduit-floor. Fig. 7 is a plan, full size, of a portion of the pusher formed with teeth or forwarding-fingers of different lengths, the line *xx* indicating the position of the lower edges of the conduit-floors; also showing the adjoining extremities of the containing-channels and illustrating the use of both the curved and angular forms of type-check or lateral deviation in the line of the channels. Figs. 8 and 9 are longitudinal 90 sections through portions of the containing-channels, illustrating the prepared frictional surface for assisting in maintaining the position of the type-columns. Fig. 10 is a plan of a receiver formed with converging radial depressions or grooves for guiding the types longitudinally into the mouth of the conduit, and Fig. 11 a transverse section of the same upon plane of line *yy*, Fig. 10, looking toward the entrance of the type-passage. Fig. 12 is a view 95 similar to Fig. 7, showing the preferable form of constructing the side walls of the containing-channels for the purpose of preventing "back-lash."

In general construction and operation the apparatus is substantially the same as that described in our application, Serial No. 156,604, the receiving-plates being supported upon a carriage, C, which may be reciprocated by means of a rack and pinion, the latter in the present 100 case consisting of a segmental gear, c, provided with a lever, c', instead of the crank attachment before used.

The plates B are formed, preferably, from sheet metal, with the wide-mouthed receivers 105 b, which conduct the types into the channels b' for transfer to the conduit-plates. The construction is substantially the same as heretofore, except that each receiver b is formed with a suitable number of corrugations, b², 110 which converge toward the mouth of the passages b' for the purpose of guiding the types

into the latter heel first. This construction will be readily understood by reference to Figs. 10 and 11.

Five superimposed receiving-plates are used in the present case for the purpose of affording wider receiving-surfaces, the width of five conduits thus being rendered available for this purpose. The lower plate, as heretofore, rests upon a shelf or web, C, connecting the two standards C' C'', from which project the posts D D, against which suitable shoulders formed upon all the plates rest, as in the application referred to. These posts D D are extended upward sufficiently above the plates to afford 15 suitable means for attaching the adjustable presser-feet or binders E, by means of which the plates may be readily secured in position upon their carriage C. The binders E consist of a lateral extension or foot, e, attached to a 20 sleeve or socket, e', which is attached to the post D by a set-screw, e'', by means of which the foot e may be forced against the upper surface of the upper plate to lock the plates together.

25 The carriage C is supported in position at the rear by one or more ratchet-braces, R, which engage notches or teeth r, formed upon the rail e' or other stationary part of the apparatus. This pawl has to be raised in order 30 to retract the carriage and plates, but falls automatically into position during the forward movement of the carriage, preventing accidental movement, and, in conjunction with the buffer or stop f, firmly locking the carriage 35 and insuring the proper relation of the receiving and conduit plates.

The forward position of the receiving-plates is gaged with accuracy and the conduit-plates relieved from all danger of jar, &c., by the 40 use of one or more adjustable buffers or stops, f, which receive the impact of the forward movement of the plate-carriage C. As shown in the drawings, the adjustable stop f consists of the slotted plate f', formed with the buffer-arm f'', and secured to a stationary part of the apparatus by set-screws f' f'', as shown in Fig. 3.

The construction may be varied more or less, the essential feature being an adjustable 50 stop or buffer interposed between the conduit-plate and the receiver-plate carriage.

The vertical conduit-plates G, which are formed from sheet metal struck up into the required shape, are supported between vertical shoulders h h, formed in the uprights H H, secured rigidly to the frame-work of the apparatus. The extremities of the conduit-plates rest loosely in the grooves formed between the shoulders h h, so that the plates are free to be 60 withdrawn vertically at any time.

When the apparatus is designed for a single size of type only, the conduit-plates may be made of a single piece of sheet metal; but when designed for use in connection with 65 types of different sizes we make it in two sections, G' and G'', the upper one, G', formed

with conduits of the full width of the largest type to be used, while the lower section, G'', is formed with conduits the side walls of which converge downward from the width of 70 the largest type at top to the width of the smaller type for which it is especially designed at the bottom. Consequently a series of these lower plates with converging channels will be used in connection with each apparatus corresponding in number and minimum width to the various sizes of types to be accommodated.

By making the conduits of sheet metal shaped under hydraulic pressure their cost is not only materially decreased, but they are also 80 rendered more complete and uniform in construction as compared one with another, so that they may readily be interchanged or substituted without affecting the perfect working of the apparatus.

The lower extremity, g, of each conduit-floor extends down beyond the side walls, so as to project into the containing-channel underneath, and is either curved concavely or inclined outwardly, as shown in Fig. 6, for the 90 double purpose of breaking or retarding the vertical fall of the type at and lowering it gently into the channel, as well as to remove the face of the last preceding types beyond the line of descent of the heel of the next succeeding type even though the pusher may not yet have forwarded the preceding type. This is 95 illustrated in Fig. 6, the descending type being indicated by the dotted lines. In said Fig. 6 the types are represented in solid lines as situated just after the descent of the last type into 100 position in the channel and preparatory to the advance of the pusher, under the action of which the whole column of type is forwarded a distance equivalent to the thickness of a single type, so that upon the retreat of the pusher 105 a space of that capacity will be again afforded for the reception of the next succeeding type.

Since it is desirable that each type should be forwarded by the pusher P a distance equal 110 only to about its thickness, in order to avoid all unnecessary space between the last type forwarded and the lower end of the type-conduit, we construct the pusher-fingers p of different lengths, as shown in Fig. 7. Otherwise 115 in construction and operation the pusher P is the same as that shown and described in our application, Serial No. 156,604, last referred to. The length of each finger p is proportionate to the thickness of the particular type which it is 120 designed to forward, as will be seen by reference to Fig. 7, in which the pusher is represented as having just completed the forwarding of the types in the channels Q. The line x x represents the position of the lower edges of the 125 conduit-floors, and it will be observed that the projection of the pusher-fingers beyond such line is in each channel equal to the thickness of the types contained therein. All looseness and play at the point of transfer is 130 thus avoided and all the types are subject to like conditions. This feature is of especial im-

portance in securing and preserving the perfect alignment of the types in the containing-channels. The latter are also of special construction, being each, as shown in Figs. 7 and 12, formed with either a single or double lateral bend or angle, q . This is accomplished by bending the side walls laterally, so that they are parallel, as shown in Fig. 7, or the side walls may be bent inward at different points, as shown in Fig. 12, the object in either case being to "break" the line or cause it to deviate. This deviation from the right line of the channel may be made of greater or less extent, as desired, the essential feature being such an alteration in the line of the channel at or near its receiving end as shall subject the types to slightly more friction against the side walls than they encounter in the rest of the channel. By this means, while but slight resistance is offered to the action of the pusher, the types are supported against the backlash or retractile tendency which is apt to exist in a long column of type. The simplicity of the construction is also an advantage, all auxiliary attachments, &c., and undue pressure upon the type being avoided. One or both side walls of the type-channels Q are slightly corrugated or otherwise roughened upon the inner surface for the purpose of counteracting the tendency of the type line to move longitudinally in the channels while the latter are being transferred or otherwise handled. This construction is indicated at q' in Figs. 7, 8, and 9.

In transferring the channels it is designed to incline them laterally, so that the types will all rest against the roughened surface q' of the side wall. This construction also has a tendency to counteract all vibration or backlash, and may in some cases be relied upon exclusively for this purpose, as with the types of largest size, both side walls being thus prepared for a portion of their length at or near the receiving end; but the greater portion of at least one side of the channel should in all cases be left free and smooth to facilitate the descent of the type when resting thereon in the setter-case.

Since the two conduit-plates G G' , placed back to back, as heretofore, are necessarily placed some distance apart in order to accommodate the double reciprocating pusher P , their vertical position creates an intervening space which we utilize for the reception of a series of compartments, i i , which are supported upon a shelf, I , or by other suitable means. These compartments constitute convenient receptacles for the reception of spaces, odd sorts, &c., not provided for in the conduit-plates.

60 The conduit-plate G' upon the right side of the receiving-bank is provided with the cup-plate or guard g^2 , for facilitating the insertion of the types into the conduits upon that side.

For the purpose of adapting the apparatus to series of channels of different length, we make each type-channel bed S in two sections,

S' S^2 , which are made relatively adjustable by means of screws s s . The outer section, S^2 , upon each side of the apparatus rests loosely upon the horizontal members of the frame T , and is provided with threaded lugs s' s' , which engage the screws s , secured to the lugs s^2 s^2 upon the stationary sections S' , by means which will permit of the rotation of the screws by crank-keys or other actuating devices applied to their outer ends, s^3 s^3 , which are shouldered.

What we claim as our invention, and desire to secure by Letters Patent, is—

1. In a type-distributing apparatus substantially such as described, the combination, with the series of superposed receiving-plates and supporting-carriage, of the binders E , secured to and adjustable upon the supporting-posts D , substantially in the manner and for the purpose described.

2. In a type-distributing apparatus substantially such as designated, the combination, with a receiver-plate carriage mounted upon suitable parallel ways and adapted to be slid back and forth from or to a vertical conduit-plate, of a pawl upon the said sliding carriage and an engaging stationary rack parallel to the said ways, for the purpose and substantially in the manner described.

3. In a type-distributing apparatus substantially such as described, the combination, with the vertical conduit-plate, of a frame provided with vertical ways for the reception and support of the ends of the said vertical conduit, for the purpose and substantially in the manner described.

4. In a type-distributing apparatus substantially such as designated, a reciprocating-comb type-forwarder formed with pusher-teeth of different and prescribed lengths, for the purpose described, in combination with the type-containing channels and the conduit-plate above, substantially in the manner and for the purpose described.

5. In a type-distributing apparatus substantially such as designated, a type-containing channel formed with an internal bend or protuberance which contracts the type-passage upon one or both side walls, for the purpose and substantially in the manner described.

6. In a type-distributing apparatus substantially such as designated, a type-containing channel the side walls of which are each formed with an internal projection which contracts the type-passage, the said internal protuberance being formed at different points in the channel, but approximating each other, substantially in the manner and for the purpose described.

7. In a type-distributing apparatus substantially such as designated, a type-channel one of the inner side walls of which is corrugated or otherwise roughened, for the purpose and substantially in the manner described.

8. In a type-distributing apparatus sub-

stantially such as designated, the combination, with the two vertical conduit-plates arranged back to back, substantially as described, of an intermediate back brace or shelf, I, between them, for the purpose and substantially in the manner described.

5. In a type-distributing apparatus substantially such as designated, a type-channel bed or support formed in two sections, one of

which is adjustable with relation to the other, to substantially in the manner and for the purpose described.
